UNITED STATES PATENT OFFICE.

JOSEPH HERVE ROUSSEAU AND ALEXIS COTÉ, OF TROIS PISTOLES, QUEBEC, CANADA.

FLOUR-MILL.

1,344,453.

Specification of Letters Patent. Patented June 22, 1920.

Application filed December 4, 1918, Serial No. 265,293. Renewed April 24, 1920. Serial No. 376,425.

To all whom it may concern:

Be it known that we, JOSEPH HERVE ROUSSEAU and ALEXIS COTÉ, subjects of the King of Great Britain, residing at Trois Pistoles, county of Temiscouata, Province of Quebec, Dominion of Canada, have invented certain new and useful Improvements in Flour-Mills, of which the following is a specification.

10 The present invention relates to improvements in flour mills in which the grain is ground and the fine flour is separated from the bran by a specially constructed rotary sifter. The grain is delivered from a hopper down into a movable shoe which spreads the grain evenly over a screw which feeds the grinding plates. The meal as it falls from the grinding plates enters a chute which feeds it into the rotary sifter where 15 the flour is separated from the bran, both falling into separate chutes.

The main object of the invention is to provide preferably a manually operated grinding mill, of simple and durable construction and particularly cheap, in order that it may be obtainable by all farmers or any household, for making flour for personal use.

Another object of the invention is to provide a grinding mill of such a character that the grain may be ground and the flour separated from the bran in the same operation.

A further object of the present invention is to provide a machine of this character in which the grinding plates or stones may be moved close together to grind a finer meal by pushing a pin which is operated by a thumb screw nut.

40 A further object of the invention is to provide a sifter of cone shape whereby the fine meal will fall through the smaller portion of the sifter and the bran will naturally be carried down the larger end of the sifter and made to fall into a separate chute.

The invention will be better understood with the aid of the accompanying drawings in which:

Figure 1 is a side elevation of the machine.

Fig. 2 is an end elevation of the machine. Fig. 3 is a top view of the machine the hopper having been removed.

Fig. 4 is a longitudinal section through the sifter casing and chutes.

Fig. 5 is a perspective view of the grind-

ing plates and attachment to regulate the fineness of the grinding.

Fig. 6 is a top view of the hopper.

Fig. 7 is a detail view of the shoe rocking attachment, the driving shaft being shown in section.

Fig. 8 is a view of one end of the sifter.

Fig. 9 is a longitudinal section through one of the grinding plates, driving shaft and adjusting attachment.

Like numerals of reference indicate corresponding parts in each figure.

In the drawings, 1 is a table and 2 are supporting standards suitably secured thereto. On said table 1 is rigidly fixed a base 3 adapted to receive the driving shaft 4 having intermediate thereof the feeding screw 5 and on which is mounted at one end the movable grinding plate 6. The companion grinding plate 7 is rigidly fixed to the base 3 and the covering member 8, which latter is provided with an elongated opening 9 corresponding to the feeding screw 5; and 10 is an open ended casing or hopper upwardly projecting from said member 8.

11 is a hopper secured above said casing or hopper 10, by the arms 12; and 13 is a sliding plate for controlling the grain feeding.

Below said hopper 11 is provided a shoe 14 which is pivotally secured on the bracket 15; and 16 is an arm which is connected at one end to said shoe 14, the lower end being forked to engage an eccentric 17 which is mounted on said driving shaft 4. The arm 16 is pivotally connected intermediate of its length to a lug 18 projecting from said bracket 15, whereby the eccentric will cause said arm 16 to swing from one side to the other, thus imparting a to and fro movement to the shoe with the result that the grain will be evenly distributed to the feeding screw.

The driving shaft 4 is suitably journaled in bearings provided in the base 3 and the member 8, said shaft being provided at one end with a reduced portion 19 forming a shoulder; and 20 is a collar abutting against the bearings provided on the base 3 and member 8, said collar being provided with ball bearings abutting against the shoulder on said shaft 4 thus lessening considerably the friction. On the reduced portion 19 of shaft 4 are rigidly mounted a small pulley 21, a fly wheel 22 having a handle 23, and

a driving pulley 24 to drive the machine by any motive power should it be found more convenient.

At the opposite end of said shaft 4, is 5 rigidly mounted a supplementary crank handle 25, so that two persons may operate the machine if required.

The shaft 4, at this end is provided with a longitudinal bore or socket 26 and 27 is 10 a slot formed transversely through the shaft and communicating with said bore 26. 28 is a collar slidably mounted on said shaft adjacent said slot 27 and the movable grinding plate 6, and is provided with a central 15 transverse slot 29. 30 is a grinding member adapted to engage the slot 29 in said collar 28 and slidable within the slot 27. The said guiding member 30 is provided with a hole 31. 32 is a pin movable in the bore 26 20 and fitting at one end in the hole 31 in said guiding member 30. The other end of said pin projects outward from said bore 26 and is operated by the threaded nut 33 which is provided with the wings 34 and engages the 25 threaded portion 35 on the outer end of said shaft 4. It will readily be understood that on turning said nut 33 in the proper direction, the pin 32 will be pushed forward, thus adjusting the movable grinding 30 plate 6 against the fixed plate 7, so that the meal will be ground finer. For obtaining a coarser meal it is necessary to unscrew the nut 33.

The grain when crushed between the 35 grinding plates 6 and 7 passes through the funnel shaped chute 36 and falls into the rotatable sifter 37 mounted on the shaft 38 which is journaled in suitable bearings in the casing 39 which is preferably secured under the table 1. The said casing is provided 40 with a flour chute 40 projecting below the said sifter 37; and 41 is a bran chute adjacent said flour chute and projecting below said sifter, at one end thereof.

45 The sifter or sieve 37 is preferably of frusto-conical shape, the larger end being in alinement with the bran chute 41. It will thus be seen that the finer meal or flour

entering the smaller portion of the sifter will naturally be divided or sorted from the 50 coarser meal or bran according to its ability to pass through the meshes of the sieve, and will fall through the sifter into the flour chute 40, while the bran will naturally, by gravity, be carried down to the larger 55 end of the sifter and drop into the chute 41 through the apertures 42, when the said sifter is rotated by the pulley 43 which is connected to the driving pulley 21 by the belt 44.

It will readily be seen from the foregoing description and drawings that the device is not only of simple construction, but is also compact, which renders the machine practically indispensable to farmers and even in 65 households.

What we claim as our invention is:

In a grinding mill, the combination of a casing; a shaft journaled therein and formed with a transverse slot which extends 70 transversely through it and is located adjacent the movable grinding plate, and with a longitudinal bore opening at its inner end into said slot and at its outer end through the corresponding end of the shaft, said 75 shaft end being externally threaded; an endwise movable pin slidably fitting in said bore and projecting at opposite ends through the bore ends; a guide member extending endwise through said slot between 80 the inner end of the pin and the movable grinding plate and slidably laterally along the slot so as to transmit the endwise movements of said pin to said plate to shift the latter toward or from the fixed grinding 85 plate; and an adjusting nut for operating said pin fitted on the threaded end of the shaft and engaged with the projecting outer end of the pin.

Signed at Trois Pistoles this twenty 90 fourth day of July, 1918.

JOSEPH HERVE ROUSSEAU.

ALEXIS COTE.
